HYDRAULIC CONTROL SYSTEM

Raymond S. Miller, Hollywood, and George W. Sinclair, Los Angeles, Calif., assignors to M. O. Johnston, Glendale, Calif.

Application April 28, 1949, Serial No. 90,254

13 Claims. (Cl. 60—52)

1

This invention relates to a fluid pressure system and to control means therefor. More particularly, it relates to an hydraulic system for erecting and operating a portable, collapsible rig used in drilling and servicing oil wells.

The fluid pressure system of this invention has particular application to the erection and operation of a rig such as described in copending application of Mac J. Kinsey et al., Serial No. 89,322, filed April 23, 1949, now abandoned, entitled "Portable Drilling Rig."

An object of this invention is to provide a fluid pressure system and control means therefor which can be operated from the cab of a vehicle carrying a collapsible drilling rig for erecting the rig, and which can also be remotely controlled after erection of the rig and during drilling and servicing of the well, at some point of vantage.

It is a further object of this invention to provide a fluid pressure system which is operable to handle large volumes of liquid under pressure to control the operation of a plurality of hydraulic cylinders, each having a large piston area and a long piston stroke.

It is a still further object of the invention to provide a fluid pressure system which combines safety features and features of automatic operation rendering the erection and operation of a large oil well derrick simple, expeditious and safe.

One form which the invention may assume is exemplified in the following description and illustrated by way of example in the accompanying drawings, in which:

Fig. 1 is a diagrammatic view of the hydraulic control system of the invention and of a group of hydraulic cylinders controlled thereby.

Fig. 2 is a view in section of the valve means for controlling the hydraulic ram and auxiliary or cat cylinders during erection of a portable rig.

Fig. 3 is a more or less diagrammatic view showing the main part of the control system of Fig. 1 in detail.

Referring now to the drawings and more particularly to Fig. 1, there is shown an hydraulic control system generally designated as 10 and a group of hydraulic cylinders generally designated as 11. The hydraulic cylinders 11 are of the nestable tube type, and they are described in detail in the copending application above-mentioned. Only so much of their structure and operation is described herein as is necessary to an understanding of the present invention.

Two main cylinders 12 are shown, each having a liner 13, a piston 14 reciprocable in the liner and nestable, telescoping tubes 15 secured at the

5 top to the cylinder and at the bottom to the piston. The liner 13 is spaced from the cylinder to provide an annular space 17a for passage of fluid to and from the liner. An air pressure line 16 communicates with each cylinder 12 beneath the piston, and an hydraulic pressure line 17 communicates with the annular space 17a between the liner and cylinder. An air bleed line 18 is provided, as illustrated, and a cable or wire line 19 is attached at one end to the piston, is led over a sheave 20 and is attached at its other end to a hook 21 which serves to carry a load.

It is apparent that, as hydraulic pressure is supplied to the main cylinders 12 through lines 17, the pistons 14 will be depressed against the air pressure therebelow and the hook 21 will be lifted, thus lifting a load or doing other useful work. If hydraulic pressure is held steady in the main cylinders, the load will be held stationary, and if hydraulic pressure is bled from the cylinders the load will be lowered.

As also illustrated, the main cylinders are sectional in construction, comprising upper and lower sections 12a and 12b, respectively, coupled at 22.

25 A pair of auxiliary or cat cylinders 30a and 30b are also illustrated, these being similar in construction and operation to the main cylinders. Each cat cylinder has a liner 31 in which a piston 32 is reciprocable, and nestable tubes 33 and a cable or wire line 34 led over a sheave 35 are also provided as illustrated. An air pressure line 36 and an hydraulic pressure line 37 are provided, as in the case of the main cylinders. As also illustrated, an hydraulic ram 40 is provided for use 30 during erection of the derrick as described in the above-mentioned copending application.

35 The hydraulic ram 40 is operated by a pair of parallel pumps 41 (of which only one is shown). For simplicity, only one such pump 41 will be referred to hereinafter. Pump 41 is preferably a positive displacement pump capable of developing a high pressure, e. g. 1800 p. s. i., such as needed during erection of the derrick described in the above-mentioned copending application. Pump 41 is also used to operate the cat cylinders 30a and 30b during erection of the derrick. Centrifugal pumps 42 and 43 are used to operate both the cat cylinders 30a and 30b and the main cylinders 12 after erection of the derrick and during drilling and servicing of a well. The reason for this arrangement of pumps is, that during erection or rigging up a high pressure is of major importance while speed and the rapid handling of large volumes of liquid is of lesser importance. But 40 during drilling or servicing a well, lower pressures

are acceptable but the pumps should be capable of rapidly handling large volumes of liquid for the sake of speed. Centrifugal pumps capable of delivering 950 p. s. i. are suitable for this purpose.

Pump 41 and pumps 42 and 43 are operated by engines 44 and 45 through suitable mechanical linkages (not shown) including clutches (not shown) to disengage either set of pumps while the other set is operating. Engines 44 and 45 are throttled as follows: A lever 50 is connected by a mechanical linkage 51 to an hydraulic servo unit 52 which is connected through lines 53 and 54 to hydraulic slave units 55 and 56 which in turn are connected to engines 44 and 45 by mechanical linkages 57 and 58, respectively. On moving lever 50 upwardly as viewed in Fig. 1 from its neutral position, the engines 44 and 45 are accelerated through the medium of the hydraulic units 52, 55 and 56 and fluid links 53 and 54.

During preliminary operations such as rigging up a portable derrick of the character referred to, when maximum pressure is desired, the ram 40 and cat cylinders 30a and 30b are operated by positive displacement pump 41 through the medium of control levers 59 and 60. Lever 59 controls the ram 40 and lever 60 controls cat cylinders 30a and 30b. In Fig. 1 the control systems for the ram and cat cylinders are shown in simplified form and in Fig. 2 they are shown in greater detail. Referring to Fig. 1, the control lever 59 for ram 40 is connected by a mechanical linkage 65 to a valve structure 66. Hydraulic fluid is supplied from a reservoir 67 through lines 68 and 69 to pump 41 and fluid under pressure passes through a line 70 having a check valve 71 to the valve structure 66, thence through a line 72 to the ram. When pressure is bled from the ram, fluid passes back through the line 72 to valve structure 66, thence through a line 73 to line 68 and back to reservoir 67. A line 74 is also provided for telescoping the ram in the manner described hereinafter.

Control lever 63 for cat cylinders 30a and 30b is connected by a mechanical linkage 80 to a valve structure 81. As stated, the engines 44 and 45 are throttled by lever 50. Lever 50 also controls valves 82 in lines 83 which lead to the cat cylinders, by means of a slip link 84 of known construction. Thus, when lever 50 is in its neutral position, slip link 84 holds valves 82 in closed position; i. e., it prevents pressure draining from cat cylinders 30a and 30b when pump 41 is not developing a pressure. When, however, lever 50 is advanced to accelerate engines 44 and 45, slip link 84 is released and valves 82 may be operated by a lever 85.

Still referring to Fig. 1, and assuming that valves 82 are open, pressure reaches the cat cylinders from pump 41 through a line 86, valve structure 81, a line 87, valves 82, lines 83 (which also contain throttle valves 88) and lines 37. Pressure is bled from the cat cylinders through lines 37 and 83 (throttle valves 88 serving to restrict the rate of bleed), valves 82 and line 87 to valve structure 81, thence through a line 89 to line 73 and to the reservoir 67.

Referring now to Fig. 2, ram control valve 66 comprises a tubular housing 100 within which a piston 101 is reciprocable. The piston 101 is operated by a lever 59, and it is formed with lands 102, 103 and 104. Ram 40 comprises the usual telescopic section 40a, 40b and 40c. Section 40a is formed with longitudinal passages 105 and 106. Passage 105 extends through a piston 107 formed as part of section 40a while passage 106 opens

behind the piston 107. As shown, passages 105 and 106 communicate with lines 72 and 74, respectively.

To extend the ram 40, lever 59 is moved to the right as viewed in Fig. 2, thus moving piston 101 to the right and communicating ports 108 and 109 formed in the housing 100. Pressure passes to the ram through line 70, ports 108 and 109, line 72 and passage 105, thus extending the ram. To hold pressure in the ram at any given position, lever 59 is returned to its vertical, neutral position. Land 103 shuts off pump pressure through port 108, and the pump communicates with the reservoir 67 through a passage 110 and a port 111 formed in housing 100, a line 112, ports 113 and 114 formed in valve structure 81, a line 115 having a check valve 116 and line 73. Pump pressure is maintained in ram 40 through a line 117 leading from line 115 to line 72, as shown, and having a check valve 118.

To bleed pressure from the ram, lever 59 is moved to the left, thus moving land 103 so as to uncover port 109 and cover port 108 and moving land 102 to uncover a port 125. Pressure drains from the ram through line 72, port 109, a port 126 and a line 127, thence through a port 128, a passage 129 and a port 130 formed in valve structure 81 to line 89, and then through line 73 to the reservoir 67. Meanwhile, pump pressure is delivered through line 70, ports 108 and 125 in housing 100 and line 74 to passage 106 in section 40a of the ram, thus exciting a thrust on the lower end of section 40b and forcing the ram to telescope.

During operation of the ram 40, cat cylinder control lever 60 is maintained in neutral position as illustrated. When it is desired to operate the cat cylinders, the ram control lever 59 is returned to neutral position. To supply pressure to the cat cylinders, lever 60 is moved to the right. It will be seen that lever 60 operates a piston 131 which is reciprocable in housing 132. The piston 131 is provided with lands 133, 133a, 134, and 135. When lever 60 is moved to the right, fluid pressure passes from the pump 41 through line 70, ports 108 and 136 in housing 100, a line 137, ports 138 and 139 in housing 132 and line 87 to the cat cylinders. Fluid pressure also passes through a passage 132a formed in housing 132 to a recess or cavity 132b and therefrom to port 154 which is uncovered by land 133.

To hold pressure in the cat cylinders, lever 60 is returned to neutral position, thus closing port 139 to prevent return of pressure therethrough and holding pressure in the cat cylinders.

To bleed pressure from the cat cylinders, lever 60 is moved to the left, thus communicating port 139 with passage 129 and allowing pressure to bleed through line 87, port 139, passage 129, port 130, line 89, etc. back to the reservoir.

As is also shown, the valve housings 100 and 132 are formed with recesses 140 and 141, respectively, communicating through a line 142, a port 143 and a passage 144 communicating with port 130 and thence with the reservoir. Thus, provision is made for bleeding off fluid that may leak past lands 102 and 133a. Also, provision is made for relieving pump pressure in excess of the pressures for which the ram and cat cylinders are designed. Thus, in a typical case the ram 40 is designed for a maximum pressure of 1800 p. s. i. and the cat cylinders 30a and 30b for a maximum pressure of 900 p. s. i. For the purpose of relieving excess pressure, pressure relief valves 150 and 151 of the Vickers C-167

type are provided. These valves are of standard, well known type and require no detailed description here. Valve 150 will be set to open at 1800 p. s. i. when activated by pump pressure through a line 152 and at a lower pressure when actuated through a line 153. Valve 151 will be set to open at 900 p. s. i. when actuated by pump pressure through a port 154 in housing 132 and a line 155 and it communicates with valve 150 through the line 153. Thus, when the ram 40 is operating, land 133 will close port 154 (thus keeping pump pressure from opening valve 151). If pump pressure exceeds 1800 p. s. i., valve 150 will open and pressure will bleed through a line 156 to the reservoir. When the pump pressure returns to 1800 p. s. i., valve 150 will close.

When the cat cylinders 30a and 30b are operating and pressure is being supplied thereto, land 133 will have been moved to the right to open port 154, thus communicating pump pressure with valve 151 through recess 132b and passage 132a. Should the pump pressure exceed 900 p. s. i., valve 151 will open, pressure will be communicated through line 153 to valve 150 and the latter will open, thus relieving pump pressure as described above.

As stated, the cat cylinders 30a and 30b and the ram 40 are employed during erection of the derrick and they are controlled by levers 50, 59, 60 and 85, which may be conveniently located in the cab of a vehicle employed to carry the derrick along with other elements of the rig such as the engines 44 and 45 and pumps 41, 42 and 43. When the derrick has been erected and is ready for operation to drill or service a well, a control panel 170 (see Fig. 1) is set up at some point of vantage where the operator or derrickman has an unobstructed view of the derrick.

The control panel 170 is of conventional construction and requires no detailed description. Thus it comprises a master control lever 171 which rides in an H-shaped slot (not shown) and is, therefore, capable of movement to the left and right in a horizontal plane and is also capable of movement up and down at either end of its horizontal travel. Briefly, movement of lever 171 to the left places the pumps 42 and 43 in parallel and movement thereof to the right places the pumps 42 and 43 in series. Movement of the lever 171 downwardly accelerates the engines 44 and 45 and thus delivers pump pressure, while movement of this lever upwardly from its neutral position controls pressure bleed from the main cylinders 12. Left- and right-hand cat cylinder control levers 172a and 172b are also provided. Movement of the cat cylinder control lever 172a downwardly from its neutral position accelerates the engines 44 and 45 and thus delivers pressure to the left-hand cat cylinder 30a, while movement of such lever upwardly from its neutral position controls pressure bleed from the left-hand cat cylinder. Similarly, downward and upward movement of the right-hand cat cylinder control lever 172b from its neutral position, delivers pressure to the right-hand cat cylinder or controls pressure bleed therefrom, respectively.

Valve structures 173, 174, 175, 176 and 177 control the main cylinders 12, while valve structures 178a and 178b control the left- and right-hand cat cylinders 30a and 30b, respectively. Valve structures 178a and 178b are identical and they are described in detail in copending application of Raymond S. Miller et al., Serial No. 89,321, filed April 23, 1949, now Patent No. 2,639,693

issued May 26, 1953, entitled "Hydraulic Control Valve and System." Valve structure 173 is described in detail in copending application of Raymond S. Miller, Serial No. 89,326, filed April 23, 1949 (now abandoned), entitled "System Check Valve."

Each of the control levers 171, 172a and 172b has a mechanical linkage generally designated as 179 with a servo unit 180 connected by lines 181 and 182 with hydraulic slave units 183 and 184, which control engines 44 and 45, respectively. As stated, downward movement of any of the control levers 171, 172a and 172b operates to accelerate the engines 44 and 45 and thus to deliver pump pressure to the cylinders.

The left-hand cat cylinder control lever 172a also has a mechanical connection designated as 185 with a servo unit 186 which is connected by lines 187 with an hydraulic unit 188 and through lines 187 and 195 with an hydraulic unit 196 which is operatively connected with and forms a part of the left-hand cat cylinder control valve structure 172a. Similarly, the right-hand cat cylinder control lever 172b has a mechanical connection 198 with a servo unit 188 and through lines 200 and 201 with an hydraulic unit 202 which is operatively connected with and forms a part of the right-hand cat cylinder control valve structure 172b.

Master control lever 171 is connected by a mechanical linkage 204 with a servo unit 205 and by a mechanical linkage 206 with a servo unit 207. The servo unit 205 is connected by lines 208 to an hydraulic unit 209 which is operatively connected to and forms a part of the valve structure 175. Since servo unit 205 and hydraulic unit 209 are connected by two lines (see lines 208, Fig. 3), piston 226 will be moved to the right or left when lever 171 is shifted to the right depending only on how lines 208 extending from unit 205 are connected to unit 209. In the present instance, the lines are connected so that when lever 171 moves to the right, piston 226 is moved to the left, and consequently when lever 171 is moved to the left, piston 226 will be moved to the right. Servo unit 207 is connected by lines 211 with an hydraulic unit 212 which is operatively connected to and forms a part of valve structure 174. Hydraulic unit 212 is also operatively connected to a valve 213 by means generally designated as 214.

Air pressure for the system is provided by a compressor unit 220 connected to a reservoir 221 through a line 222. Other elements of the air pressure supply and relief means are described hereinafter in connection with the operation of the system.

It will be understood that Fig. 1 is greatly simplified. Further details are provided hereinafter with particular reference to Fig. 3.

As stated, if it is desired to operate pumps 42 and 43 in series (for greater pressure), master control lever 171 is moved to the right, and if it is desired to operate the pumps 42 and 43 in parallel, lever 171 is moved to the left. This control is effected in the following manner.

Referring to Fig. 3, it will be seen that unit 203 comprises a tubular housing 225 in which a piston 226 having a stem 227 and lands 223 and 224 is reciprocable. As is also shown in Fig. 3, valve structure 175 comprises a valve 230 controlling a port 231 and operated by a piston 232 reciprocable in a chamber 232a. Assuming it is desired to operate the pumps 42 and 43 in series, lever 171 is moved to the right, thus activating

servo-unit 205 which causes the fluid to flow through lines 208 in such a direction as to drive piston 225 to the left, thus communicating a port 233 with a port 234. Pump pressure in a line 235 reaches port 233 through lines 236 and 237, and passes thence through port 234 and a line 238 into chamber 232a beneath piston 232. Thus piston 232 is quickly elevated and valve 230 is quickly opened. Fluid from reservoir 67 passes through lines 73 and 239 to pump 42, thence through a line 245 and port 231 to pump 43. A check valve 246 in valve structure 176 controls a port 247 communicating with reservoir pressure in a line 248. Obviously, since pump pressure exists to the left of valve 246 and tank or reservoir pressure to the right thereof, valve 246 will remain closed and the only path by which fluid can reach pump 43 is from pump 42 through line 245, port 231 and a port 249 in valve structure 176. The pumps are, therefore, in series. Pressure passes from pump 43 through line 235 to the cat cylinders or the main cylinders as explained hereinafter.

If it is desired to operate pumps 42 and 43 in parallel, master control lever 171 is moved to the left, thus activating servo-unit 205 which causes the fluid to flow through lines 208 in such a direction as to drive piston 226 of unit 209 to the right and communicating port 233 with a port 250. Pump pressure passes through line 237, port 233, port 250 and a line 251 to chamber 232a above piston 232, thus quickly closing valve 230. Fluid from reservoir 67 reaches pump 42 through lines 73 and 239. Since pressure from pump 42 is unable to reach valve 246, the latter is free to open under the pressure existing in reservoir 67. Fluid therefor reaches pump 43 through line 248 and ports 247 and 249 in valve structure 176. Pressure from pump 42 passes through line 245, a line 255, and a port 256 in valve structure 177 which is controlled by a check valve 257. (It will be noted that during series operation of the pumps 42 and 43, the pump pressure in valve structure 177 exceeds that in line 255, and that as a consequence valve 257 is held closed.) Pressure from pump 43 passes through line 235. Unit 209 is also provided with ports 258 and 259 which communicate through lines 260 and 260a with the reservoir, to drain fluid displaced by movement of piston 226.

If it is desired to operate the main cylinders 12, master control lever 171 is moved to the right or left, as desired, to operate pumps 42 and 43 in series or in parallel as described. To supply pressure to the cylinders, lever 171 is moved downwardly from neutral position, thus accelerating engines 44 and 45 and delivering pressure to the valve structure 177 in the manner described.

It will be seen that valve structure 173 includes a port 265 controlled by a check valve 266, and a port 267. During operation of the main cylinders, pump pressure in valve structure 177 is free to open valve 266, which thus passes through ports 265 and 267 into a line 268. Pressure then passes through ports 269 and 270 in valve structure 174 into a line 271, thence into lines 17 and cylinders 12 (see Fig. 1).

Valve structure 174 includes a pilot operated valve 272 controlling a port 273 which communicates with line 248, hence with reservoir 67. To supply pressure to cylinders 12, lever 171 is moved downwardly, and it is of course necessary to close valve 272 so that pump pressure in line 266 will not return to the reservoir through port 273 and

line 248. This is accomplished by means of servo-unit 207 and hydraulic unit 212.

As shown in Fig. 3, unit 212 and valve structure 174 form parts of a pilot operated valve mechanism of known type which need not be described in detail. Suffice it to say that when lever 171 is depressed, it actuates unit 212 to open a pilot valve (not shown) which admits pump pressure from line 268 above a piston 274 to close valve 272, thus accomplishing the desired result. Alternatively, hydraulic control means acting directly on the piston 274 may be used, of the type described hereinabove with reference to valve structure 175.

15 To hold pressure in the main cylinders 12, lever 171 is returned to neutral position. Return of pressure to the pumps is prevented by check valve 266 in valve structure 173, and return of pressure to the reservoir through line 248 is prevented by valve 272, which remains closed.

To bleed pressure from the main cylinders, lever 171 is moved upwardly from neutral position. This actuates servo unit 207 and unit 212 oppositely with respect to their operation during downward movement of the lever 171, thus draining pump pressure from above piston 274 and delivering pump pressure therebelow to raise the piston and with it the valve 272. Fluid drains from the cylinders through port 273 and line 248, at a rate determined by the position of lever 171.

If it is desired to operate the left hand cat cylinder 30a and to deliver pressure thereto, lever 172a is moved downwardly from its neutral position. This accelerates engines 44 and 45 and provides pump pressure in the manner described hereinabove. It also operates in the manner now to be described to prevent pump pressure from reaching the main cylinders.

Referring again to Fig. 3, it will be seen that hydraulic unit 188 comprises identical slave units 280a and 280b for the left- and right-hand cat cylinders, respectively. Each unit 280a or 280b comprises a piston 281 reciprocable in a cylinder 282 and having a stem or rod 283 which engages a pawl 284. Each pawl 284 engages a lug 285 on a rod 286 which is urged downwardly by a spring 287 and which has a cam 288 at its upper end. The unit 188 also comprises an hydraulic unit 289 comprising a rod 290 having a roller 290a at one end engaging the cam 288 and lands 291, 292 and 293 which are reciprocable in a cylinder 294. A spring 295 normally urges rod 290 to the left. Pump pressure is communicated to cylinder 294 through a line 296 and pressure relief lines 297a and 297b are provided for removal of fluid displaced by movement of the rod and lands.

60 Hydraulic unit 289 operates a valve mechanism 313. The valve mechanism 310 comprises pistons 311 and 312 reciprocable in a cylinder 313 and connected by a stem or rod 314 and a land 315.

65 In operation, the unit 188 and valve 310 function as follows: When lever 172a is moved downwardly from neutral position to deliver pump pressure to the left-hand cat cylinder, it also actuates servo unit 186 (see Fig. 1) and thereby delivers pressure to the left of piston 281 in slave unit 280a. Rod 283 is thereby moved to the right and rocks pawl 284. Pawl 284 urges rod 286 upwardly, thus moving land 292 of unit 70 289 to the right. Pressure line 296 is thereby

communicated with a line 316 and moves piston 311 of valve 310 to the right. Pump pressure from line 237 is thereby permitted to pass through ports 317 and 318 in valve 310, thence through a line 319 to valve structure 173. Valve structure 173 includes a piston 323 reciprocable in a cylinder 324. Pump pressure delivered in the manner above mentioned above piston 323 will act to depress piston 320 and close valve 266. Inasmuch as the same pressure, i. e., pump pressure, is excited on both valve 266 and piston 320, and since piston 320 has a greater area, obviously valve 266 will remain closed and pressure cannot reach the main cylinders.

It will be apparent that normally, when both levers 172a and 172b are in neutral position, pressure will be applied to piston 312 of valve 310, through a line 318a. Thus, except when pressure is being supplied to one of the cat cylinders, valve 266 of valve structure 173 will be free to open. However, it will also be apparent that if pressure is being supplied to either of the cat cylinders, one or the other of the slave units 280a and 280b will act to hold valve 266 in closed position.

Pressure reaches the left-hand cat cylinder 30a through line 236, valve structure 178a, a line 322 and line 37. Valve structure 178a is operated by lever 172a, servo unit 186 and hydraulic unit 196. The valve structure 178a and hydraulic unit 196 are shown diagrammatically and in greatly simplified form in Fig. 1 but are shown in greater detail in Fig. 3.

Referring to Fig. 3, hydraulic unit 196 comprises two slave units 320 and 323 which are actuated oppositely by servo unit 186. Unit 320 operates a valve 324 through the medium of a pilot valve (not shown) and a piston 325. Valve 324 controls an inlet port 326 and it is provided with a spring 327 so as to act as a check valve. Similarly, unit 323 controls a valve 328 through the medium of a pilot valve (not shown) and a piston 329. Valve 328 controls an outlet port 330.

Valve structures 178a and hydraulic unit 196 are described in detail in the above-mentioned Patent No. 2,639,693.

In operation, when the left-hand cat cylinder control lever 172a is moved downwardly from neutral position, and engines 44 and 45 are thereby accelerated, slave unit 320 operates to open inlet valve 324 and slave unit 323 operates to close outlet valve 328. Pressure is thus delivered to the left-hand cat cylinder 30a at a rate determined by the position of lever 172a. If it is desired to hold pressure in the left-hand cat cylinder, the lever 172a is returned to neutral position. Valve 324, acting as a check valve, prevents return of pressure to the pumps and valve 328 remains closed to prevent bleed of pressure to the reservoir.

If it is desired to bleed pressure from the left-hand cat cylinders, lever 172a is moved upwardly from neutral position, thus actuating servo unit 186 which in turn actuates units 320 and 323 so as to open outlet valve 328, thus allowing pressure to bleed from the left-hand cat cylinder through lines 37 and 322, a line 331, port 330, a line 332, and lines 239 and 73 to the reservoir 67. The rate of bleed is controlled by the position of lever 172a.

The right-hand cat cylinder 30b is operated similarly by lever 172b, servo unit 199, hydraulic unit 202 and valve structure 179b. Unit 202 and valve structure 179b are identical with unit 196

and valve structure 178a, respectively, and similar parts are similarly numbered.

As stated hereinabove, air pressure for the main cylinders 12 and cat cylinders 30a and 30b is provided by a pump 220. Air reservoir 221 is connected through a line 340 to lines 16 and 36 which communicate with the main cylinders 12 and cat cylinders 30a and 30b, respectively. Thus, air pressure is maintained at all times in these cylinders beneath their respective pistons, to assist in elevating the pistons and to provide a cushion when the pistons drop. Line 340 is provided with valves 341 and 342 for a purpose explained hereinafter. Air bleed lines 18 connect through a three-way valve 343 with a line 344 which communicates with reservoir 67. Air pressure line 340 also connects with valve 343 through a line 345.

The air pressure supply and relief system thus described operates as follows: Valve 213a in line 344 is normally closed. However, when the main control lever 171 is moved to up position (i. e., when hydraulic pressure is being bled from the main cylinders), hydraulic unit 212 is, of course, actuated as described above, and this unit acts to open valve 213a, thus allowing air pressure to bleed from the main cylinders. The orifices connecting main cylinders 12 with the air bleed lines 18 are, however, very small so that only an insignificant amount of liquid is lost from the cylinders. However, this bleed is sufficient to prevent a large accumulation of air in the main cylinders above pistons 14. When lever 171 is in its neutral position to hold a load steady it is, of course, important that no pressure be lost from the main cylinders. This object is accomplished by automatic closing of the valve 213a.

When it is desired to dismantle the main cylinders, it is important that the level of hydraulic fluid not exceed the point of coupling 22, and that pressure be relieved from the cylinders before they are uncoupled. This object is accomplished as follows: Air pressure from compressor 220 through lines 340 and 16 will elevate pistons 14, thus expelling hydraulic fluid from liners 13. The pistons 14 are latched or otherwise held in elevated position and valve 343 is set to deliver air pressure through air bleed lines 18 to the top of the main cylinders, thus forcing hydraulic fluid out through lines 17 to the reservoir until the fluid level is below the couplings 22. Meanwhile, valve 341 will have been closed, and after expulsion of the hydraulic fluid, valve 342 will be opened to vent air pressure from the cylinders, which may be assisted by lowering pistons 14. The cylinders may then be safely uncoupled and the upper and lower sections 12a and 12b appropriately capped.

It will be apparent that the control means described can be operated by other means than hydraulic pressure, e. g. by pneumatic pressure. The control means and the hydraulic system controlled thereby are flexible and capable of a multiplicity of functions and are characterized by numerous advantages.

Thus, an hydraulic system and control means therefore are provided which are used during preliminary operations, such as erecting a portable, collapsible derrick, such system comprising positive displacement pumps capable of delivering a high pressure. The control means for this system is operable to operate either a ram or hydraulic cylinders, and to erect the ram, apply pressure to pistons in the hydraulic cyl-

inders, hold pressure in these devices and bleed pressure therefrom. All such operations are subject to exact control.

A main hydraulic system is also provided including a pair of centrifugal pumps capable of handling larger volumes of liquid and also including a pair of main cylinders and a pair of auxiliary cylinders. The control means for this main system is such that the pumps can be operated in series or in parallel and that when the auxiliary cylinders are being supplied with hydraulic fluid, such fluid cannot reach the main cylinders from the pumps. Nicety and rapidity of control are important characteristics of this system and its control means, and numerous safety features are embodied therein so as to ensure rapid and safe operation.

Having thus described our invention, what we claim and desire to secure by Letters Patent is:

1. An hydraulic system comprising a cylinder, a piston reciprocable therein to lift a load when hydraulic pressure is applied to said piston and to lower a load when hydraulic pressure is bled from said cylinder, a pump, an engine for operating said pump, inlet valve means including a check valve operable to feed pressure from said pump to said cylinder, said check valve being operable to prevent return of pressure to said pump, outlet valve means operable to bleed pressure from said cylinder, and control means operable by fluid pressure for throttling said engine and thereby controlling pump pressure and for operating said outlet valve means to bleed pressure from said cylinder when said engine is idling.

2. An hydraulic system comprising a cylinder, a piston reciprocable therein to lift a load when hydraulic pressure is applied to said piston and to lower a load when hydraulic pressure is bled from said cylinder, a pair of pumps, an engine for operating each pump, valve means operable to operate said pumps in series or in parallel, inlet valve means including a check valve operable to feed pressure from said pumps to said cylinder, said check valve being operable to prevent return of pressure to said pumps, outlet valve means operable to bleed pressure from said cylinder, and control means operable by fluid pressure for throttling said engines and thereby controlling pump pressure, for operating said valve means to operate said pumps in series or in parallel, and for operating said outlet valve means to close the same when pump pressure is being developed and for opening the same when said engines are idling.

3. A fluid pressure system comprising a fluid pressure device including a cylinder and a piston reciprocable therein to lift a load when fluid pressure is applied to said piston and to lower a load when pressure is bled from said cylinder, a pair of pumps, engines for operating the same, valve means for operating said pumps in series or in parallel, valve means for controlling pressure bleed from said cylinder and control means for automatically operating said engines and both of said valve means.

4. An hydraulic system comprising an hydraulic device including a cylinder and a piston reciprocable therein to lift a load when fluid pressure is applied to the piston and to lower a load when pressure is bled from said cylinder, a pair of pumps and engines for operating the same, valve means for operating said pumps in series or in parallel, valve means for controlling pressure bleed from said cylinder, and master

control means for automatically operating said engines and both of said valve means.

5. A fluid pressure system comprising a main cylinder and an auxiliary cylinder each having a piston reciprocable therein to lift a load when fluid pressure is applied to said piston and to lower a load when fluid pressure is bled from said cylinder, a pump and an engine for operating the same, inlet and outlet valve means for said auxiliary cylinder for feeding fluid pressure thereto and for bleeding pressure therefrom, inlet and outlet valve means for supplying fluid pressure from said pump to said main cylinder and for bleeding pressure therefrom, respectively, and automatic control means operable to control said engine and thereby control pump pressure, and to control said valve means and thereby deliver pressure to or bleed pressure from said cylinders.

20 6. An hydraulic system comprising a pump and an engine for operating the same, a main cylinder having a piston reciprocable therein for lifting a load when hydraulic pressure is applied to said piston and for lowering a load when hydraulic pressure is bled from said cylinder, an auxiliary cylinder having a piston reciprocable therein for lifting a load when hydraulic pressure is applied to said piston and for lowering a load when hydraulic pressure is bled from said cylinder, inlet and outlet valve means for said main cylinder operable to deliver pressure from said pump to said cylinder and to bleed pressure from said cylinder, respectively, inlet and outlet valve means for said auxiliary cylinder operable to deliver pressure from said pump to said auxiliary cylinder and to bleed pressure therefrom, respectively, and fluid pressure operated control means for throttling said engine and for operating said valve means, to selectively deliver pressure to, hold pressure in or bleed pressure from said cylinders.

45 7. An hydraulic system comprising a pair of pumps and an engine for each pump, valve means operable to operate said pumps in parallel or in series, a main cylinder having a piston reciprocable therein for lifting a load when hydraulic pressure is applied to said piston and for lowering a load when pressure is bled from said cylinder, an auxiliary cylinder having a piston reciprocable therein for lifting a load when hydraulic pressure is applied to said piston and for lowering a load when pressure is bled from said cylinder, inlet and outlet valve means for said main cylinder operable to deliver hydraulic pressure from said pump to said main cylinder and to bleed pressure from said main cylinder, respectively, inlet and outlet valve means for said auxiliary cylinder operable to deliver pressure from said pumps to said auxiliary cylinder and to bleed pressure therefrom, respectively, and fluid pressure operated control means operable to throttle said engine and to operate all of said valve means to selectively deliver pressure to, hold pressure in and bleed pressure from said cylinders.

70 8. An hydraulic system comprising a pair of main cylinders each having a piston reciprocable therein for lifting a load when hydraulic pressure is applied to said piston and for lowering a load when pressure is bled from said cylinders, left- and right-hand auxiliary cylinders each having a piston reciprocable therein for lifting a load when hydraulic pressure is applied to said piston and for lowering a load when said pres-

sure is bled from said auxiliary cylinders, a pair of pumps, an engine for each pump, pump valve means operable to operate said pumps in parallel or in series, inlet and outlet valve means for said main cylinders operable to deliver hydraulic pressure from said pumps simultaneously to said main cylinders and to bleed pressure simultaneously from said main cylinders, respectively, inlet and outlet valve means for each said auxiliary cylinder operable independently to deliver hydraulic pressure from said pumps to each of said auxiliary cylinders and to bleed pressure therefrom, respectively, and master control means comprising a fluid pressure means for operating said pump valve means, a fluid pressure means for operating said main cylinder valve means, fluid pressure means for independently operating said auxiliary cylinder valve means, fluid pressure means for operating each engine, and means for actuating each said fluid pressure means.

9. An hydraulic system comprising a main cylinder and an auxiliary cylinder each having a piston reciprocable therein, pump means for providing hydraulic pressure, main cylinder supply means for delivering hydraulic pressure from said pump means to said main cylinder, said supply means including inlet valve means operable by external fluid pressure and also operable as a check valve to prevent return of pressure to said pump means, auxiliary supply means for delivering hydraulic pressure from said pump means to said auxiliary cylinder, said auxiliary supply means including an inlet valve, auxiliary control means operable to open said inlet valve to said auxiliary cylinder, to control pump pressure and to close the inlet valve to said main cylinder by means of fluid pressure, and control means for said main cylinder operable to supply pump pressure thereto and to control pump pressure.

10. An hydraulically operable oil well rig, comprising a pair of upright main cylinders each having a piston reciprocable therein, a wire line for each said cylinder fixed at one end to the piston of said cylinder, right-hand and left-hand auxiliary cylinders each having a piston reciprocable therein, a wire line for each said auxiliary cylinder and fixed at one end to the piston of said cylinder, pump means for providing hydraulic pressure, pump valve means for operating said pumps in series or in parallel, engine means for operating said pump means, fluid pressure operated control means for said engine means operable to throttle the same, main cylinder supply means for supplying pump pressure to said main cylinders and for bleeding pressure therefrom, and including a fluid pressure actuated check valve operable as an inlet valve for said main cylinders and as a check valve to prevent return of pressure from said main cylinders to said pumps, auxiliary supply means for supplying pump pressure to said auxiliary cylinders including an auxiliary inlet valve and means for operating the same so as to apply fluid pressure to and close said main cylinder inlet valve when said auxiliary inlet valve is open, other valve means operable to supply pressure independently to said auxiliary cylinders and bleed pressure therefrom, said other valve means being also operable as a check valve to prevent return of pressure to said pumps, and master control means operable by fluid pressure to operate said pump valve means, said engine control means, main cylinder supply means and other valve

means so as to automatically supply pressure to, hold pressure in, or bleed pressure from said auxiliary cylinders in unison or separately and to supply pressure to, hold pressure in, or bleed pressure from said main cylinders in unison.

11. An hydraulic system comprising a reservoir for supplying fluid to the system, a first conduit from said reservoir to the intake port of a first pump, a second conduit from said reservoir to the intake port of a second pump, a third conduit from the output port of said second pump to an hydraulic motor, a fourth conduit from the output port of said first pump communicating with the third conduit, a fifth conduit communicating with said fourth conduit with said second conduit, circuit control valve means adapted to be positively opened and closed, said valve means located in said fifth conduit, a spring loaded check valve located in the second conduit intermediate the reservoir and the communicating fifth conduit, a spring loaded check valve located in the fourth conduit intermediate the communicating third and fifth conduits, inlet valve means adapted to be positively opened and closed and including a spring loaded check valve, said inlet valve means being located in the third conduit intermediate the hydraulic motor and the point of communication between the third and fourth conduits, a return conduit connected to said third conduit intermediate the hydraulic motor and the intake valve means, said return conduit communicating with said reservoir, outlet valve means adapted to be positively opened and closed for bleeding pressure from said hydraulic motor, said outlet valve means located in said return conduit, an engine for operating said first and second pumps, control means for throttling said engine and thereby controlling the output of said pumps, and valve control means for positively opening and closing said circuit control valve means whereby when said circuit control valve means is positively moved to the open position said check valves located in said second and fourth conduits move to the closed positions and said pumps operate in a series circuit, and when said circuit control valve means is positively moved to the closed position, said check valves located in said second and fourth conduits move to the open position and said pumps operate in a parallel circuit, said control means being also operable to positively open and close said inlet valve means whereby there is a positive control of fluid to said hydraulic motor, said control valve means also being operable to positively open said outlet valve means to bleed pressure from said hydraulic motor.

12. An hydraulic system as described in claim 11 including a sixth conduit connected to said third conduit intermediate said second pump and inlet valve in said third conduit and communicating with an auxiliary hydraulic motor, inlet valve means located in said sixth conduit adapted to be positively opened and closed, a seventh conduit connected to said sixth conduit intermediate said inlet valve and said auxiliary hydraulic motor and communicating with said reservoir, and an outlet valve means operable to be positively opened and closed, said outlet valve located in said seventh conduit, whereby when said valve control means positively closes said inlet valve located in said third conduit said inlet valve means located in said sixth conduit is positively opened and said outlet valve means in said seventh conduit is closed and hydraulic pressure is supplied to said auxiliary hydraulic

motor, said valve control means operable to positively close said inlet valve means located in said sixth conduit and open said outlet valve in said seventh conduit to bleed pressure from said auxiliary hydraulic motor.

13. An hydraulic system comprising a cylinder, a piston reciprocable therein to lift a load when hydraulic pressure is applied to said piston and to lower a load when hydraulic pressure is bled from said cylinder, a pump, an engine for operating said pump, inlet valve means including a spring loaded check valve, said inlet valve means operable to feed and cut off pressure from said pump to said cylinder and to prevent return of pressure from said cylinder to said pump, outlet valve means intermediate said inlet valve means and said cylinder operable to bleed pressure from said cylinder, and a single control means operable by movement in one direction for throttling said engine and thereby controlling pump pressure and while retaining a desired pump pressure operable by movement in another direction for closing said inlet valve and opening

5 or closing said outlet valve to bleed or retain pressure from or in said cylinder.
